MOTOR CONTROL SYSTEM

Fred M. Parks, Murrysville, Pa., assignor to Westinghouse Electric & Manufacturing Company, East Pittsburgh, Pa., a corporation of Pennsylvania

Application April 14, 1934, Serial No. 720,598

6 Claims. (Cl. 172—239)

My invention relates to motor control systems and has special reference to systems of the so-called "synchronous tie" type.

One object of my invention is to control the operation of a motor responsive to the movement, or variations in movement, of an element of a device that is to be controlled by the motor.

Another object of my invention is to control the starting and stopping of a motor in response to variations in position of an element of a device the operation of which is to be controlled by the motor.

A further object of my invention is to control the operation of a motor driving a device to compensate for certain changes in operation of the device.

A still further object of my invention is to provide a control for a motor wherein the change in position, or the starting and stopping of the motor, will correct for the change in the operation of the device driven by the motor which initiates such variation in position of starting and stopping of the motor.

A more specific object of my invention is to maintain, for example, the top of a gas accumulator tank, where the supply is variable, in a definite position by controlling a throttle valve in the demand line; or to maintain a definite tension on a strip of paper or steel between sections or roll stands.

Other objects and advantages will become more apparent from a study of the following specification when considered in conjunction with the accompanying drawing, in which:

Figure 1 is a diagrammatic showing of the novel features of my invention as applied to a gas accumulator tank using two "synchro-tie" units or systems; and

Fig. 2 is a schematic showing of certain mechanical features of my invention, used with a gas accumulator tank, when only one "synchro-tie" unit or system is used.

Referring more particularly to Fig. 1 of the drawing, a gas accumulator tank 17 comprises a movable top 2 and a fixed base 18. The movable top 2 is suitably mechanically coupled to the transmitter 1 of a "synchro-tie" system 15. The receiver 3 of the "synchro-tie" system is mechanically coupled to a regulator 4 whereby the demand that may be put on the supply of gas in the tank may be regulated by the throttle valve 7. The throttle valve 7 is mechanically coupled to a motor 6 which may be operated either to open or to close the throttle valve, as will be pointed out more in detail hereinafter. The motor 6 is

mechanically coupled to a transmitter 5 of a second "synchro-tie" system 16. The receiver 9 of the "synchro-tie" system 16 is also coupled to the regulator through the mechanical gearing 13.

As is well known, for a "synchro-tie" system or connection, the receiver motor follows movements of the transmitter motor very exactly which therefore means that any variation of the height of the tank 2 will be reflected by a corresponding movement of the member 11 actuated by the receiver 3 through the gear mechanism 10.

The member 11 is coupled to a mercoid switch 12 which is pivotally mounted on a vertically movable member 14. Any vertical movement of the member 11 will initiate the operation of the motor 6 which thereupon will operate the transmitter 5 and the throttle valve 7. The receiver motor 9, as is well known for "synchro-tie" connections, follows the transmitter motor 5, thereby moving the vertically movable member 14 through the gear mechanism 13 in such a direction as to return the mercoid switch 12 to the position shown in Fig. 1. In this position the energizing circuit for the motor 6 is interrupted and the actuation of the throttle valve 7 is halted. If the correction was not sufficient at one operation of the motor 6, and the top 2 continues to move in its original direction of motion, the cycle of operation just explained is repeated again and again, if necessary, thereby effecting the desired correction for the position of the throttle valve in small increments until the limit of travel for the valve has been reached.

To state the foregoing operation more in detail, let it be assumed that the demand on the demand line or pipe 8 is such as to cause a lowering of the top 2 of the tank 17. The top 2 is coupled to a sheave 21 on the shaft of the transmitter 1 through the cable 22. To provide for the proper cooperative action between the top 2, the cable 22, and the sheave 21, a weight 23 is hung at one end of the cable that traverses one of the sheaves 24 of a crown block in the installation, is wound to the extent of several turns on the sheave 21, traverses a second sheave 24 in the crown block, and has its other end attached to the top 2.

The "synchro-tie" systems 15 and 16 are connected by single phase stator windings for the respective motors shown to a suitable source of alternating current indicated by the buses 19. The secondary windings of the respective transmitters and receivers are interconnected so that neither the rotors of the transmitters nor the receivers will rotate under normal conditions.

If, however, as has been assumed, the sheave 21 is rotated, the armature of the transmitter 1 is rotated and circulating currents are set up in the interconnected armature windings of the transmitter and receiver of the "synchro-tie" system 15 with the result that the shaft of the receiver 3 drives the gearing connection 10 to move the vertically movable member 11, let us say, downwardly in proportion to the rotation of the sheave 21.

10 The downward movement of the member 11 tilts the mercoid switch 12 on the pivot 25 upon the vertically movable member 14 and an energizing circuit is established for the motor 6 through the lower contact member 26 and the contact member 27 of the mercoid switch 12. The motor 6 shown is a split-series motor, although any other reversible motor would be satisfactory and, upon the movement of the mercoid switch 12 just explained, will operate 20 in such a direction as to shut off the gas moving into the demand line 8.

25 Operation of the motor 6 drives the shaft of the transmitter 5 through the gearing 28. The "synchro-tie" system 16 is similar in every respect to the "synchro-tie" system 15 and in consequence the armature of the receiver 9 will be rotated exactly the same amount that the armature of the transmitter 5 is rotated by the motor 6. The 30 vertically movable member 14 is thus moved downwardly through the gearing 13 and since such movement moves the pivot point 25 downwardly, the mercoid switch 12 will be tilted to the position shown in both figures, whereupon the operation of the motor 6 ceases. If the top 35 2 continues to move downwardly, the cycle of operation just explained is repeated again and again, if necessary, until the limit of travel for the member 14 is reached at which point the 40 throttle valve 7 is completely closed, preventing the flow of any gas into the demand line or pipe 8.

45 If the demand decreases, thus causing a rise in the level of the tank 2, the mercoid switch 12 will be tilted towards the left and the motor 6 will be caused to operate to open the throttle valve 7. The vertically movable member 14 will thereupon be actuated in an upward direction to interrupt the energizing circuit for the motor 50 6.

The foregoing control system for the gas accumulator tank 11 thus provides an accurate, reliable and cheap means of controlling the position of the top 2 of the tank 17.

55 In some installations, where the receiver 3 need not be located at a remote place but can be positioned at the tank, there is no real need for a "synchro-tie" connection such as shown at 15. In such case, as is shown in Fig. 2, the movement 60 of the top 2 may influence the position of the mercoid switch directly through a mechanical coupling. The regulator 4 with regard to the vertically movable member 14 will, however, still be controlled by the "synchro-tie" connection 16, shown in Fig. 1. The control of the position 65 of the top 2 may thus be very economically effected without the "synchro-tie" connection 15.

70 The control system hereinbefore described is not limited to the control of the position of the top of a gas accumulator tank but has general application and may, of course, be readily used in the paper mill industry where two or more machines are to be controlled so as to follow exactly the operations of a main machine or a 75 control motor or a pilot means.

My system of control is also of utility in the steel industry where a strip of material being rolled is to be rolled under a fixed tension.

Those skilled in the art after having had the benefit of the teachings of my invention can 5 readily apply my invention to the apparatus I have suggested and there is, therefore, no need to show in detail how my system of control might be used with such other apparatus. I wish, therefore, to be limited only by the claims ap- 10 pended hereto and any pertinent prior art.

I claim as my invention:

1. In a system of control, in combination, a member the position of which is to be controlled, a synchro-tie system including a transmitter motor and a receiver motor, said transmitter motor being coupled to the member, a second synchro-tie system including a transmitter motor and a receiver motor, a reversing motor connected to aid in positioning said member in one or the other direction and also coupled to drive said last-named transmitter motor, a slidable member, a switch pivotally mounted on the slidable member and adapted to control the direction of operation of said reversing motor, and coupling means for effecting operation of said pivotally mounted switch from one receiver motor and a sliding movement for the slidable member from the other receiver motor. 30

2. In a system of control, in combination, a member the position of which is to be controlled, a synchro-tie system including a transmitter motor and a receiver motor, said transmitter motor being coupled to the member, a second synchro-tie system including a transmitter motor and a receiver motor, a reversing motor connected to aid in positioning said member in one or the other direction and also coupled to drive said last-named transmitter motor, a slid- 35 able member connected to the receiver motor of the second named synchro-tie system, and a switch pivotally mounted on the slidable member and connected to be tilted by the receiver motor of the first named synchro-tie system, 40 said switch being adapted to control the direction of rotation of said reversible motor. 45

3. In a system of control, in combination, a member the position of which is to be controlled, a reversible motor coupled to aid in positioning said member in one or the other direction, a synchro-tie system including a transmitter motor and a receiver motor, said transmitter motor being coupled to said reversible motor, a slidable member coupled to said receiver motor, 50 a switch pivotally mounted on the slidable member and adapted to control the direction of rotation of said reversible motor, and means adapted to tilt said pivotally mounted switch in response to movements of the first-named member. 55

4. In a system of control, in combination, devices whose operating characteristics are to be held within a certain range relative to each other, a synchro-tie system including a transmitter motor and a receiver motor, said transmitter motor being coupled to be operable by variations of said certain range, a second synchro-tie system including a transmitter motor and a receiver motor, a reversible motor adapt- 65 ed to produce effects to counteract variations in said certain range, a slidable member, a switch pivotally mounted on said member and adapted to control the direction of operation of said reversible motor, and coupling means for 70 75

effecting tilting of said switch from one receiver motor and a sliding movement from the other receiver motor.

5. In a system of control, in combination, devices whose operating characteristics are to be held within a certain range relative to each other, a synchro-tie system including a transmitter motor and a receiver motor, said transmitter motor being coupled to be operable by variations of said 10 certain range, a second synchro-tie system including a transmitter motor and a receiver motor, a reversible motor adapted to produce effects to counteract variations in said certain range, a 15 slidable member connected to the receiver motor of the second named synchro-tie system, and a switch pivotally mounted on the slidable members and connected to be tilted by the receiver motor of the first-named synchro-tie system.

said switch being adapted to control the direction of rotation of said reversible motor.

6. In a system of control, in combination, devices whose operating characteristics are to be held within a certain range relative to each other, 5 a reversible motor coupled to aid in maintaining said certain range, a synchro-tie system including a transmitter motor and a receiver motor, said transmitter motor being coupled to be driven by said reversible motor, a slidable 10 member adapted to be slidably operated by said receiver motor, a switch pivotally mounted on the slidable member and adapted to control the direction of rotation of said reversible motor, and means adapted to tilt said switch in response to variations in the operating characteristics relative to each other and said devices. 15
